ANIMAL SLIPPER

James W. Jackson, 7914 W. Country Club Drive,
Overland Park, Kans. 66212

Filed Mar. 22, 1972, Ser. No. 337,244

Term of patent 14 years

Int. Cl. D30—99

U.S. Cl. D30—34

Fig. 1.

Fig. 2.

Fig. 3.

Fig. 6.

Fig. 4.

Fig. 5.

FIG. 1 is a top plan view of the animal slipper of the present invention in a collapsed position;

FIG. 2 is an elevational view of one side of the animal slipper, the other side being substantially similar thereto, as shown in FIG. 1;

FIG. 3 is an elevational view from the front of the animal slipper, as shown in FIG. 1;

FIG. 4 is a side elevational view of the animal slipper in an open position to receive the foot of an animal;

FIG. 5 is an elevational view looking into the open cavity of the animal slipper from the rear when the slipper is in the open position of FIG. 4;

FIG. 6 is a front elevational view of the animal slipper as it would appear when positioned on an animal's foot; and

FIG. 7 is a rear elevational view of the slipper in the position shown in FIG. 6.

I claim:

The ornamental design for an animal slipper, as shown and described.
